UNITED STATES PATENT OFFICE.

GEORGE W. FRENCH, OF CHICAGO, ILLINOIS.

TOY.

Application filed February 12, 1921, Serial No. 444,315.

To all whom it may concern:

Be it known that I, GEORGE W. FRENCH, a citizen of the United States, residing at 306 South Wabash Avenue, Chicago, in the 5 county of Cook and State of Illinois, have invented new and useful Improvements in Toys, of which the following is a specification.

This invention relates to improvements in 10 toys and more especially to a small figure in semblance of a human.

The figure is constructed from a body part, head part, leg parts and arm parts, as will be explained more in detail hereinafter, 15 in such a manner that each figure alone, and in combination with other like figures, may be made to assume a great variety of postures, positions, and attitudes. The various parts from which each figure is formed are 20 also so constructed that they may readily be attached to and detached from each other, whether incorporated in one or more figures.

One of the features of the invention is the construction and formation of the various 25 parts comprising each figure in such a way that the figure alone and in combination with other figures in a great number of different positions, postures and attitudes will always rest in equilibrium on a horizontal 30 surface. Another feature of the invention is the construction of the various parts in such a manner that said parts may be attached together to form figures in semblance of animals, and other objects.

35 In the drawings I have shown figures embodying features of my invention, in which Fig. 1 is a view in front elevation of such a figure, Fig. 2 is a view in side elevation of the same, Figs. 3 to 8 are views showing examples of some of the different positions and 40 postures that may be assumed by one of the figures, Figs. 9 to 13 are views showing some of the many different positions and postures that may be assumed by two of such figures 45 in conjunction with each other, and Fig. 14 is a view showing certain of the parts used in constructing one of the figures joined together to form a figure in semblance of an animal. The drawings are on a reduced 50 scale.

As shown in the drawings, 20 indicates in general a body part, 30 a leg part, 40 a foot part, 50 a head part and 60 an arm part. All of these parts except the arm parts are 55 cut out of material of the same thickness. As actually used, the material from which

these parts have been constructed was substantially one inch thick; although it is obvious that, without detracting from the spirit of this invention, they may be made 60 of material of any thickness. It is desirable, however, to have the material thick enough, so that the figures and various parts will stand by themselves. The arm parts are formed of material about one-third the 65 thickness of the material from which the other parts are formed. Hereafter, in describing the shapes of the various parts I will consider them as being cut from materials as mentioned, and will describe 70 merely the plane surfaces as presented by the views of these parts in elevation as shown in Fig. 1. Also in the claims, in describing the shapes of the various parts I will consider them as being planes although it is 75 obvious that they may be formed from material of any desired thickness.

As shown in the drawings 20 indicates the body part of one of the toy figures. This part is octagonal in shape with one of 80 the angles reversed and reentrant, each of the sides being one inch long. In Fig. 1 I have indicated by 24 the sides adjacent the reentrant angle 23, and the other sides by 25. The two sides 24 are the same length as the 85 sides 25, and the reentrant angle 23 is the reverse of the angle indicated by 26 which would be formed if the part 20 were a perfect octagon. The angle 26 is the same as the angles formed by any two adjacent sides 90 25, such as indicated by 30'. The broken lines 25' indicate the location of the two sides that would form the angle 26 if the part 20 were a perfect octagon.

30 indicates a leg part which is cut out of 95 material of the same thickness as the body part and is made in the form of a square, each of the sides 31 being the same length as one of the sides 25 or 24 of the body part 20.

40 indicates a foot part which is also cut out of material of the same thickness as the other parts, and is of the shape shown in the drawings. As shown in Fig. 1, the top edge 41 is of the same length as one of the sides 31 of the leg part, or sides 25 of the body part. The adjacent side 42 is of the same length as the side 41 forming an angle of 135° therewith. The bottom edge 43 lies parallel with the upper edge 41 forming an angle of 110 45° with the edge 42. The back edge 44 lies at right angles to the edges 41 and 43. It

will be noted, by referring to the body part 20 in Fig. 1, that if the upper edge 25 of such body part and the vertical line 25' are prolonged to meet as indicated by the broken lines 47 and 48 respectively that the area bounded by the two sides 24, the line 47, and the line 48 with this continuation 25' will be the same shape as the foot part 40.

The head part, indicated by 50, is also cut 10 out of material of the same thickness as the other parts, and is circular in shape with a diameter equal to the distance between two parallel sides 25 of the body part.

The arm parts 60 are cut out of material 15 of about one-third the thickness of the material from which the other parts are cut, and are substantially rectangular in shape, each being provided with a small projection 61 to indicate a thumb.

20 Holes indicated by 70 to accommodate dowel pins for fastening the parts together are provided in all of the sides of the body part, at one point in the periphery of the head part, on three sides of each leg part, 25 on the top and bottom surfaces of each foot part, and near the ends of each arm part. The holes in the body part for fastening the arms are located on each of the large flat sides near the corner formed where the two 30 sides 25 and 24 meet as indicated by 71. The holes 70 in the other surfaces of the body part are centrally located in each face, and likewise in the leg part and the upper face of the foot part. The hole 70 in the 35 lower face of the foot part is a continuation of the hole in the upper face.

The different parts may be painted the same or different colors, and the head part 40 may be decorated on each of its large sides with a face such as shown in Fig. 1.

Each figure may comprise a body part, a head part, two arm parts, two leg parts and two foot parts. It is obvious, however, that, without detracting from the spirit of this 45 invention, any of such parts may be duplicated as desired. The various parts may be joined together by the use of dowel pins such as indicated by 75 adapted to fit in the holes 70 and 71. The parts may be joined 50 together to form one figure in a great variety of postures, attitudes and positions; or two or more figures may be joined together to form various combinations. Also as indicated in Fig. 14, for example, the parts may 55 be joined together to form animals and other objects.

Fig. 1 and Figs. 3 to 8 show the parts

joined together to form a single figure in some of the different attitudes, positions and postures that may be assumed. Figs. 9 to 60 13 show a few examples of the combinations that may be made with two of the figures.

It will be noted that because of the particular construction and shape of the various parts that the various different figures constructed therefrom, whether singly, or in combination with each other, will always assume a position of rest and equilibrium on a horizontal surface. The drawings illustrate but a few of these various different 70 figures. The exact number of different figures that may be made from the parts shown, and the exact number of different positions, attitudes and postures into which the figures themselves, or in combination with each 75 other, may be made is not known; but each of these numbers is believed to be very great. But a few examples are indicated in the drawings.

While I have shown and described certain 80 embodiments of my invention, it is to be understood that it is capable of many modifications. Changes therefore in the construction and arrangement may be made without departing from the spirit and scope 85 of the invention as disclosed in the appended claims, in which it is my intention to claim all novelty inherent in my invention as broadly as possible in view of the prior art.

What I claim as new and desire to secure 90 by Letters Patent is:

1. A toy figure including a body part substantially octagonal in shape with two adjacent sides forming a reentrant angle and a detachable leg part adapted for attachment 95 to the body part in a plurality of positions.

2. A toy figure including a body part substantially octagonal in shape with two adjacent sides forming a reentrant angle and a detachable leg part adapted for attachment 100 to any one of the sides of the body part.

3. A toy figure including a body part substantially octagonal in form with one reentrant angle equal to the opposite angle, a head part attached to one side of the octagonal body part, two removable leg parts adapted to be attached to any of the sides of the body part, foot parts on the leg parts, and two arm parts and means for pivotally securing them to the body part. 110

In witness whereof I have hereunto set my hand and seal this 10th day of February, 1921.

GEORGE W. FRENCH. [L.S.]
